UNITED STATES PATENT OFFICE

127,885

DESIGN FOR A BADGE OR THE LIKE

Ramiro Monedero, San Salvador, El Salvador

Application March 25, 1941, Serial No. 99,876

Term of patent 3½ years

To all whom it may concern:

Be it known that I, Ramiro Monedero, a citizen of El Salvador, residing at San Salvador, have invented a new, original, and ornamental Design for a Badge or the like, of which the following is a specification, reference being had to the accompanying drawing, forming part thereof.

I claim:

The ornamental design for a badge or the like, as shown.

RAMIRO MONEDERO.
